UNITED STATES PATENT OFFICE.

WASHINGTON H. KILBOURN, OF GREENFIELD, MASSACHUSETTS, ASSIGNOR
OF ONE-THIRD TO ARCHIBALD D. FLOWER, OF GREENFIELD, MASSA-
CHUSETTS.

TRACK-SANDING DEVICE.

SPECIFICATION forming part of Letters Patent No. 758,141, dated April 26, 1904.

Application filed August 13, 1903. Serial No. 169,365. (No model.)

To all whom it may concern:

Be it known that I, WASHINGTON H. KILBOURN, of Greenfield, in the county of Franklin and State of Massachusetts, have invented
5 certain new and useful Improvements in
Track-Sanding Devices, of which the following is a specification.

This invention relates to that portion of a
10 street-railway track-sanding device which con-
ducts sand downwardly from a hopper or res-
ervoir; and it has for its object to provide a
conduit adapted to receive sand from an ele-
vated reservoir and to deliver the sand, whether
15 the same is wet or dry, at a uniform rate and
in any desired quantity.

Another object of the invention is to pre-
vent the obstruction of the delivery of sand
by pebbles and other relatively large pieces in
the sand.

20 The invention consists in the improvements
which I will now proceed to describe and claim.

Of the accompanying drawings, forming a
25 part of this specification, Figure 1 represents
a sectional view showing the portions of a
track-sanding device to which my invention
appertains. Fig. 2 represents a view similar
30 to Fig. 1, showing a different adjustment.
Fig. 3 is a view similar to Figs. 1 and 2, show-
ing another adjustment. Fig. 4 represents a
section on line 4 4 of Fig. 1. Fig. 5 repre-
sents a section on line 5 5 of Fig. 3.

The same reference characters indicate the
same parts in all the figures.

In the drawings, *a* represents a vertical con-
35duit, having an inlet *4* at its upper portion
and an outlet *5* at its lower portion, the con-
duit being enlarged between the inlet and out-
let to form a chamber *6*, which is horizontally
40 elongated in the direction of the movement of
the sand-supporter *b* hereinafter described.

The said sand-supporter *b* is here shown as a
substantially horizontal plate located in the
chamber *6* and separated from the top of said
chamber and from the inlet *4* by a vertical space
45 which is so proportioned to the length of the in-
let and of the supporter *b* as to cause the sup-
porter to hold a bank or accumulation of sand in
position to obstruct the inlet and prevent the

flow of sand therethrough when the supporter
is in a central position or about midway be-
50tween the extremes of its movement, as shown
in Fig. 3. When the supporter is in this posi-
tion, the angle of repose of the accumulation of
sand between the top of the chamber and the
supporter is such that the sand does not extend 55
to the ends of the supporter, as indicated by
dotted lines *xx* in Fig. 3, said lines indicating
the angle of repose of the margin of a body
of sand which has flowed through the inlet
and has accumulated on the supporter. I find 60
in practice that good results are produced by
locating the upper surface of the supporter
about half an inch below the under side of the
top of the chamber *6* and by forming the
supporter *b* so that when in its central posi- 65
tion (shown in Fig. 3) the diagonal distance
between each of its ends and the correspond-
ing end of the inlet *4* will be longer than the
surface *x* of the accumulation of sand. When,
however, the supporter bears at one end 70
against a stop adjusted to limit the longitu-
dinal movement of the supporter in such man-
ner as to prevent gravity-feed, the opposite
end of the supporter is preferably about an
inch and three-quarters from the correspond- 75
ing end of the inlet *4*.

I do not limit myself to the dimensions above
specified, as these may be varied as circum-
stances may require.

80 A longitudinal reciprocating motion is im-
parted to the supporter *b* by means of a rock-
shaft *c*, journaled in bearings in the sides of the
conduit *a*, an arm *c'*, affixed to the rock-shaft
within the conduit and engaged at its upper
end with the supporter, and suitable devices 85
for oscillating the rock-shaft, said devices com-
prising, preferably, a pedal *c''* on the car-plat-
form, arranged to be depressed by the foot of
the motorman, a bell-crank lever *c''*, pivoted be-
low the platform and having one arm in con- 90
tact with the pedal *c''*, and a rod *c''*, connecting
the other arm of the bell-crank lever *c''* with
an arm *c''*, affixed to the rock-shaft *c*. A spring
95 *c''* holds the supporter *b* normally at one end
of its movement against a stop *d*. When the
treadle *c''* is depressed, the rock-shaft and the

arm c' are moved in the direction indicated by the arrow in Fig. 1, the supporter b being correspondingly moved in the same direction until its motion is arrested by a stop e . The supporter during this movement carries a part of the accumulation of sand along with it, and when the movement of the supporter is arrested a portion of this sand falls over the end of the supporter and passes through the outlet 5 10 15 20 25 30 35 40 45 50 55 60

5. When the treadle c^2 is released, the spring c^6 moves the supporter b in the opposite direction until it is arrested by the stop d . The stop d is preferably adjustable, so that it may be retracted, as shown in Fig. 2, until it permits the supporter to move endwise far enough to bring one of its ends within the angle of repose of the sand, thus allowing the sand to flow continuously by gravitation over the end of the supporter, as indicated in Fig. 2. The rapidity of this gravity - feed will depend on the adjustment of the stop d . When the stop d is adjusted inwardly, as shown in Fig. 1, the angle of repose of the sand will not extend over the end of the supporter. Hence endwise movement of the supporter, as above described, is necessary in order to effect a discharge of the sand. The stop e may also be adjustable to vary the extent of movement of the supporter toward the said stop.

It will be seen that the supporter located below the inlet and separated therefrom by a vertical space, which permits sand to accumulate on the supporter below the inlet, not only enables the supporter to hold the accumulation of sand in position to obstruct the inlet, but also prevents any possibility of the packing or clogging of the sand in the inlet in consequence of the dampness of the sand or presence of pebbles therein.

It will be observed that the conduit a is not a hopper or reservoir, but simply conducts sand from an elevated reservoir, which may be of any suitable shape and may be arranged at any suitable point, the lower portion of said reservoir communicating with the inlet 4.

If desired, the supporter b may be formed as a sieve composed of a marginal frame and a reticulated body portion or sheet of woven wire or other suitable material supported by the frame and covering the space surrounded by it. In this case the longitudinal movements of the supporter will cause the sand to pass through the meshes of the supporter; but when the supporter is standing still it will support the sand practically as it does in the solid construction here shown.

The conduit a may be secured to the floor of a car in any suitable way, and the top of the conduit may be flush with the top of the floor or may be located below the floor or flush with the bottom side thereof.

The supporter preferably rests loosely on the upper end of the arm *c* and is prevented from tipping on said arm by two longitudinal

guide lips or shoulders *i i*, formed on opposite sides of the conduit and slightly overhanging the edges of the supporter. It will be seen, therefore, that the supporter is not pressed downwardly against a fixed support by the weight of the sand resting on it and that the frictional resistance to the movements of the supporter is reduced to the minimum. The stops at the ends of the path of movement of the supporter arranged to abruptly stop the movement and cause the jarring of the sand insure an effective delivery of sand either over the end of the supporter when the same is solid or imperforate or through the body of the supporter when the latter is formed as a sieve. I claim—

I claim—

1. A track-sanding device comprising a vertical conduit having a sand-inlet at its upper portion, a sand-outlet at its lower portion, and an enlargement or chamber between said inlet and outlet, a longitudinally - movable sand-supporter located in said chamber and separated from the top of the chamber and from the said inlet by a space which permits the accumulation of a body of sand on the 90 supporter below the inlet, and means for longitudinally reciprocating the supporter to discharge sand therefrom into the lower portion of the conduit, the supporter being formed and arranged to hold the accumulation of sand 95 in position to close the said inlet.

2. A track-sanding device comprising a vertical conduit having a sand-inlet at its upper portion, a sand-outlet at its lower portion, and an enlargement or chamber between said inlet and outlet, a longitudinally-movable sand-supporter located in said chamber and separated from the top of the chamber and from said inlet by a space which permits the accumulation of a body of sand on the supporter below the inlet, said supporter being formed and arranged to hold the accumulation of sand in position to close the inlet, means for longitudinally reciprocating the supporter, said means having provisions for normally holding the supporter at one end of its movement, and an adjustable stop for varying the normal position of the supporter relatively to the inlet, whereby the supporter when in its normal position may either permit a continuous flow of sand by gravitation over one of its ends, or may entirely arrest the sand, and means for longitudinally reciprocating the supporter to cause the discharge of sand therefrom.

3. A track-sanding device comprising a vertical conduit having a sand-inlet at its upper portion, a sand-outlet at its lower portion, and an enlargement or chamber between said inlet and outlet, a longitudinally-movable sand-supporter located in said chamber and separated from the top of the chamber and from the said inlet by a space which per- 125

mits the accumulation of a body of sand on the supporter below the inlet, a rock-shaft journaled in said conduit below the supporter and having an upwardly-projecting arm engaged with the supporter, and means for oscillating said rock-shaft and arm to reciprocate the supporter and cause a discharge of sand therefrom.

4. A track - sanding device comprising a movable sand-supporter, a rock-shaft journaled below said supporter and having an upwardly-projecting arm engaged with the supporter, means for oscillating said rock-shaft to cause a discharge of sand from the supporter, a conduit inclosing the supporter and separated from the upper side thereof, and means for preventing the supporter from tipping on said arm.

5. A track - sanding device comprising a sand-supporter movable endwise, a rock-shaft

having an upwardly-projecting arm loosely engaged with the supporter and sustaining the weight thereof, and a conduit inclosing the supporter and having overhanging guides arranged to prevent the supporter from tipping 25 out of place on the arm.

6. A track-sanding device comprising a vertical conduit having a sand-inlet at its upper portion, and a sand-outlet at its lower portion, a longitudinally-movable sand-supporter located in said chamber between the inlet and outlet, means for longitudinally reciprocating the supporter, and stops at opposite ends of the supporter to arrest and jar the latter.

In testimony whereof I have affixed my signature in presence of two witnesses.
